WRITING INSTRUMENT

Gino C. Di Spirito, Hasbrouck Heights, N.J., assignor
to Kreisler Manufacturing Corporation, North Bergen,
N.J.

Filed Apr. 9, 1970, Ser. No. 22,355

Term of patent 14 years

Int. Cl. D19—06

U.S. Cl. D74—17

FIG. 1 is a side elevational view of a writing instrument showing my new design, the other side being a mirror image thereof;

FIG. 2 is a front elevational view thereof;

FIG. 3 is a rear elevational view thereof;

FIG. 4 is a top plan view thereof.

I claim:

The ornamental design for a writing instrument, substantially as shown.
